UNITED STATES PATENT OFFICE.

ANDREW J. SANFORD, OF NEWARK, OHIO.

DESIGN FOR A SUGAR-BOWL OR SIMILAR ARTICLE.

41,764.

Specification for Design.

Patented Sept. 12, 1911.

Application filed April 20, 1911. Serial No. 622,420. Term of patent 14 years.

To all whom it may concern:

Be it known that I, ANDREW J. SANFORD, a citizen of the United States, residing in Newark, county of Licking, and State of Ohio, have invented a new, original, and ornamental Design for a Sugar-Bowl or Similar Article, of which the following is a specification, reference being had to the accompanying drawing, forming a part thereof.

The drawing is a perspective view of a glass sugar bowl showing my new design.

The sugar bowl illustrated is of elliptical shape in horizontal section, having a horizontally extending Grecian band or border about its upper portion, and a series of flat facets or panels below the same.

I claim:

The ornamental design for a sugar bowl, or similar articles, as shown and described.

ANDREW J. SANFORD.
